UNITED STATES PATENT OFFICE.

CARL W. A. KOELKEBECK, OF PITTSBURGH, PENNSYLVANIA.

MUSIC RACK.

Application filed March 2, 1926. Serial No. 91,706.

My invention relates to music racks, more particularly to music racks which are adapted for changing sheet music without requiring the use of the operator's hands.

5 It is among the objects of my invention to provide a music rack embodying means for rapidly changing sheet music to give the musician an uninterrupted view of his notes during the rendition of his entire program.

10 Another object of my invention is to provide a music rack which shall be adapted for changing sheet music without requiring manipulation by the musician thereby allowing him the uninterrupted use of his hands.

15 It is another object of my invention to provide a music rack which shall be adapted for arranging in its proper order all of the sheet music of an entire program in the position in which it is read, thereby eliminating the confusion and interruptions caused by the turning and sorting of the sheets during the rendition of the music.

Another object of my invention is to produce a music rack of simple, compact and 25 durable mechanical construction provided with means for presenting the sheets of notes to the musician in their proper order with facility and dispatch.

It is the common experience of musicians 30 to interrupt their playing on account of the necessity for turning or replacing their sheet music during the playing of a musical number or between successive numbers, resulting in confusion and noticeable interruptions.

35 My present invention relates to a music rack which is intended to overcome these difficulties by providing a continuous and uninterrupted view of sheet music to the musician during the rendition of an entire musical program.

In accordance with my invention I provide a music rack comprising a table or frame supported on a suitable standard, which table is adapted to journal for rotation a plurality of winding drums in spaced relation for mounting a carrier or belt to which the sheet music is attached in the position in which it is normally read by the musician. The belt or carrier is secured at its respective ends to the drums and is adapted to be simultaneously unreeled from one of the drums and wound on the other while traversing the table member.

50 I also provide actuating mechanism for the drum members which is operated in any

suitable manner as by means of a pair of cranks provided with foot pedals.

In the accompanying drawings constituting a part hereof, and in which like reference characters designate like parts, Fig. 1 is a front elevational view of a music rack embodying the principles of my invention; Fig. 2 is a view partially in section and partially in side elevation of the rack shown in Fig. 1 taken along the line II-II thereof; Fig. 3 is a view in cross section of the table member of the rack shown in an inclined position; Fig. 4 is a partial plan view of the table and drums illustrating the position of the sheet music in traversing across the table from one drum to another; Fig. 5 is a sectional view taken along the line V-V, Fig. 4; Fig. 6 is a longitudinal sectional view partially in elevation taken along the line VI-VI, Fig. 5; Fig. 7 is a sectional view of a fragmentary portion of the table taken along the line VII-VII, Fig. 6; Figs. 8 to 12, inclusive, are plan views of the belt or carrier member to secure the sheet music which is carried by the winding drums; Fig. 13 is a sectional view taken along the line I-I, Fig. 12, and Figs. 14 to 18, inclusive, are end views of the belt members illustrating various means of fastening the strips within which the sheets of music are located.

Referring to Figs. 1, 2 and 3 of the drawings the structure therein illustrated comprises a table member 1 having extending side frame portions 2 provided with brackets 3 for rotatably journaling a pair of winding drums 4 having extending end flanges 5. The table 1 is provided with a plurality of hinge brackets 6 having openings 7 by which it is pivotally secured to a pair of hollow trunnions 8 which are fastened or integrally formed to a standard or vertically extending supporting member 9 having an expanded base 10 to provide the necessary stability for the entire structure. The central portion of the table 1 is provided with a bifurcated bracket 11 having an arm 12 pivotally secured thereto which is provided with openings 13 adapted to receive a pin 14 by means of which the arm 12 is secured in any desired position with respect to a bracket 15 laterally projecting with standard 9. By means of this adjustment the table 1 may be inclined as shown in Fig. 3 to adjust the position of the music relative to the vision of the musician.

A pair of sheave wheels 16 and 17 are rotatably mounted on the shafts 18 and 19 carrying the drums 4 both of these sheave wheels being provided with serrated clutch faces 20 on the projecting hub portions thereof. A pair of axially movable clutch members 21 having clutch faces 22 corresponding to the faces 20 of the sheave members are mounted on the shafts 18 and 19 having a splined connection therewith, and a shifting lever 23 is pivotally secured at its central portion 24, Fig. 6 to the frame of the table 1. The extended ends 25 of the levers are bifurcated and extend between the flanges 26 of the clutch 21 so that the manipulation of the lever will effect engagement of one or the other of said clutch members with its coacting clutch to effect engagement of its corresponding sheave wheel with the drum shaft. It will be noted that the lever and clutches are arranged so that either one of the clutches will be engaged to effect a driving connection while the other becomes disengaged.

Referring to Figs. 1 and 2, the standard 9 is provided with an offset portion 30 having a pair of journals 31 for rotatably mounting a crank shaft 32 provided with a crank 33 and a sheave wheel 34, the crank and sheave wheel being respectively provided with foot pedals 35, as shown. A plurality of sheave wheels 36, 37, 38 and 39 are mounted on the table frame with their respective axes in a common longitudinal plane, and having the upper faces of their grooved outer peripheries in alignment with the grooved peripheries of the sheave wheels 16 and 17. The sheave wheels 38 and 39 are in alignment with a sheave wheel 40 which is mounted on a vertically adjustable screw 41 having a hand wheel 42 for adjusting the screw relative to the sill 43 of the pedestal 9.

The sheave wheels 36 and 37 are arranged so that their approximate faces or grooved peripheries are in alignment with the peripheral grooves of the sheave wheel 34, and the wheels 38 and 39 are arranged to provide a similar alignment with the sheave wheel 40. An endless belt 45 is passed around all of the sheave wheels to provide an operative driving engagement between the foot-operated sheave wheel 34 and the driving sheaves 16 and 17 of the winding drums 4.

The disposition of the belt 45 over the sheave wheels is clearly shown in Fig. 6 of the drawings and the direction of travel of the belt for operating the winding drums is indicated by arrows. The belt is actuated by the operation of the foot pedals 35 to cause it to traverse the sheave wheel 37, the sheave wheels 38 and 39, then passing around the wheel 40, and up to and around the wheel 39, thence in a longitudinal direction to the left around the sheave wheel 16, as shown

by the arrow, from which it passes to the right around the sheave wheel 17 of the right-hand drum, thence around the sheave wheel 36 and back to the foot operated sheave wheel 34. As shown in Fig. 6 the belt passes through the openings of the hollow trunnions 8 to prevent interference of the belt for any position of the table 1. Proper tension is maintained on the belt by means of the adjustable screw 41 which carries the sheave wheel 40.

Referring to Figs. 4 and 6 of the drawings a belt or carrier 50 is secured to the winding drums 4 in the manner as will be hereinafter explained so as to cause it to traverse across the table from one drum to the other, as shown in Fig. 4. Referring to Figs. 8 to 18, inclusive, the belt or carrier 50 consists of a relatively long strip of flexible material such as cloth, leather, or any other substance of durable quality which is flexible and susceptible of being wound on the drum members 4. The belt may be provided at its ends with openings or eyelets 51 for fastening it to hooks provided on the drum member or one or both ends of the belt may be provided with hooks 52 as shown in Fig. 12. The side edges of the belt 50 are overlapped in the manner shown in Fig. 14 and secured near its edges to effect a crimping of the material to provide a convenient and accessible niche 53 within which the edges of sheet music may be located. In Figs. 9 to 15, the flaps 54 are provided by fastening an independent strip 55 to the belt 50 for the same purpose as explained in connection with Fig. 14, and as shown in Figs. 10 and 16 the strips may be divided into sections by transverse stitches 56 each section corresponding in dimensions to conveniently space and receive sheets of music which are disposed therein in side-by-side relation. In Figs. 11 and 17 an additional strip 57 is sewn or otherwise secured to the member 50 to provide means for securing two or more sheets of different sizes to the belt member, one size of sheet corresponding to the distance between the strip 57 and the lower strip, and the other size or dimension corresponding to the distance between the upper and lower strips as in the preceding figure. In Figs. 12, 13 and 18 transverse strips 58 are secured to the belt 50 to provide spacing members for gripping the sheets in addition to the grips provided by the side strips 54. Sheet music is secured in the belt 50 in the manner set forth as shown in Fig. 4 of the drawings and a belt of any desired length carrying any number of sheets of music may be wound on one of the drums 4 and extended across the table 1 to the other drum 4, the drums being spaced sufficiently to present several sheets of music to the view of the musician.

As shown in Fig. 6, the belt carrying the sheets of music passes from the underside of

the right-hand drum to the surface of the table 1 and from the table member to the lower region of the left-hand drum thereby maintaining a proper tension to keep the 5 sheets of music taut and also to prevent crimping and distortion thereof.

The operation of my music rack is briefly as follows: With the belt or carrier to which the sheet music is secured arranged in the 10 manner shown in Fig. 4, that is, with the belt wound on the right-hand drum member and one end secured to the left-hand drum member extending from the underside of the drums across the table member as previously 15 explained, the sheet music is presented to the view of the musician, and after reading the notes on both of the sheets in view he places the lever 23 in the position shown in Fig. 4, to and for engagement of the clutch 21 with the clutch faces 20 of the sheave wheel 16. This position is maintained during the subsequent unreeling of the belt from the right-hand drum and for winding of the same on the left-hand drum. The operation of the 25 foot pedals 35 by the musician will cause the left-hand drum to rotate in a clockwise direction by virtue of the spline connection of the shaft 18 with the clutch member 21 and the connection of the latter with the belt-operated sheave wheel 16, the right-hand drum being disengaged from its cooperating clutch will rotate independently of the drive mechanism, the sheave wheel 17 being disengaged from the clutch 21 will also idle on the shaft 19 thereby permitting the drum to 30 unreel at a speed corresponding to the peripheral winding speed of the left-hand drum which increases with the increase in diameter of the belt or music carrier as it is being wound thereon.

When all of the music has been passed across the supporting table in the manner described the lever 23 is shifted to disengage the clutch with the sheave wheel 16 and engage the clutch with the sheave wheel 17, by subsequent actuation of the drive mechanism, thereby unreeling the left-hand drum and winding the carrier belt on the right-hand drum, which again places the sheet music in position for use for a subsequent performance.

It is evident from the foregoing description of my invention that a music rack made in accordance therewith provides a simple and efficient means for presenting the sheet music before a musician without interruption or confusion and without subjecting the musician to any discomfort or inconvenience. It is further evident that a rack constructed in the manner herein described is 55 relatively inexpensive and can be manufactured at a cost and in such quantities as to make it available for use by musicians generally, and that from the nature of my device that it may be utilized for numerous

exhibiting purposes where it is desired to expose consecutive objects such as reading matter, pictures or the like.

Although I have described a specific embodiment of my invention it will be obvious to those skilled in the art that various modifications may be made in the design and arrangement of the several structural features as for instance in the positioning of the winding drums to have the music pass 70 in a vertical rather than a longitudinal direction as shown, without departing from the principles herein set forth.

I claim:

1. A rack comprising a standard, a table 80 hinged thereto, a plurality of drums mounted with their axes in parallel alignment to rotate in bearings on said table, a carrier wound on said drums and stretched across the said table, a crank shaft journaled in said standard having foot pedals for rotating the same, a sheave wheel mounted on said shaft, a plurality of sheave wheels mounted on the respective drum shafts, and an endless belt connecting all of said wheels. 90

2. A rack comprising a standard, a table 95 hinged thereto, a plurality of drums mounted with their axes in parallel alignment to rotate in bearings on said table, a carrier wound on said drums and stretched across the said table, a crank shaft journaled in said standard having foot pedals for rotating the same, a sheave wheel mounted on said shaft, a plurality of sheave wheels mounted on the respective drum shafts, an 100 endless belt connecting all of said wheels, and an adjustable tension device for said belt.

3. A rack comprising a standard having 105 hollow trunnions, a table having hinge straps pivoted on said trunnions, a pair of drums journaled in said table, sheave wheels mounted for rotation with said drums, a relatively long flexible strip wound on said drums, a foot operated actuating mechanism for operating said drums, a sheave wheel mounted for rotation with said mechanism, guide wheels mounted on said standard having their grooved peripheries in a plane extending through the axes of 110 said trunnions, and an endless belt passing through said trunnions and around said guide wheels for connecting the sheave wheels of said drums and actuating mechanism. 115

4. A rack comprising a standard, a table 120 hinged at one end to said standard, a pair of shafts journaled for rotation in said table with their axes in parallel alignment, drums rotatably mounted on said shafts, 125 clutch members splined on the ends of the respective shafts and adapted for axial movement thereon, sheave wheels rotatably mounted on said shafts having clutch faces adapted for engagement with said clutch 130

- members, a sheet carrier wound on said drums and extending across the table transversely of the axes of said drums, a crank shaft journalled in said standard having 5 foot pedals for rotating the same, a sheave wheel mounted on said crank shaft, and means for operatively connecting all of the said sheave wheels to actuate said drums by the operation of said foot pedals.
- 10 5. A rack comprising a standard, a table mounted thereon, a plurality of drums journalled for rotation in said table, with their axes in parallel alignment, a sheet carrier wound on said drums and stretched across 15 said table, and actuating mechanism mounted in said standard for rotating said drums, said table being adjustable on said standard to any degree of inclination from a horizontal to a vertical position.
6. A rack comprising a standard having 20 hollow trunnions, a table hinged for pivotal movement on said trunnions, a pair of drums rotatably journalled in said table, an endless carrier belt adapted to be wound on 25 said drums, sheave wheels for rotating said drums, a crank actuated sheave wheel rotatably mounted in said standard, guide wheels mounted on said standard, and an endless belt passing through said hollow 30 trunnions and around said sheave and guide wheels to operatively connect said drums and crank actuating member, the axes of said trunnions being tangent to the grooved peripheries of said guide and drum-rotating 35 wheels.

In testimony whereof, I sign my name.

CARL W. A. KOELKEBECK.
